UNITED STATES PATENT OFFICE.

IDA M. HART, OF SHARPTOWN, INDIANA.

PENCIL-HOLDER.

1,033,693.

Specification of Letters Patent. Patented July 23, 1912.

Application filed November 21, 1911. Serial No. 661,542.

To all whom it may concern:

Be it known that I, Ida M. Hart, citizen of the United States, residing at Sharptown, in the county of Franklin and State of Indiana, have invented new and useful Improvements in Pencil-Holders, of which the following is a specification.

The invention relates to pencils and more particularly to the class of combined pencils and holders therefor.

The primary object of the invention is the provision of a pencil in which a holder is permanently secured to one end thereof so as to become a part of the same so that when using the pencil it may be fastened within the pocket of a garment or on a belt of the garment so as to prevent the possibility of the loss of the pencil when not in use.

Another object of the invention is to provide a pencil of this character which is extremely simple in construction, inexpensive in manufacture, so that a pencil with the holder can be sold at a small cost, the holder being of a construction and so mounted on the pencil as not to interfere with the free use thereof.

With these and other objects in view the invention consists in the construction, combination and arrangement of parts as will be hereinafter more fully described, illustrated in the accompanying drawings, and pointed out in the claim hereunto appended.

In the drawings:—Figure 1 is an elevation of a pencil showing the attachment applied thereto. Fig. 2 is a side elevation of the attachment applied to the pencil. Fig. 3 is a sectional view on a line 3—3 of Fig. 1. Fig. 4 is a fragmentary, vertical longitudinal sectional view through the pencil and holder. Fig. 5 is a fragmentary vertical sectional view through the pencil and holder. Fig. 6 is a fragmentary side elevation of the pencil shown in Fig. 1 with the ferrule removed and partly broken away.

Similar reference characters indicate corresponding parts throughout the several views in the drawings.

Referring to the drawings by numerals, 50 10 designates a pencil which is of the ordinary well-known construction having the usual sharpened end 11, while the opposite end is provided with a reduced portion 12, on which is fixedly fitted a ferrule or sleeve 55 13, the same being provided with an eraser

tip 14, which is fastened in the ferrule or sleeve in the usual manner.

Formed in the reduced end portion 12 of the pencil 10 is a notch 15, the same being intersected at opposite ends by side grooves 16, formed in the reduced portion 12 at diametrical opposite points thereof, and in these grooves are received portions of the side limbs 17 of a substantially U-shaped resilient holder 18, which is formed from 60 a single strand of spring wire, the closed end of the holder 18 being slightly outwardly bowed as at 20' to accommodate varying thicknesses 70 of fabric material between the pencil 10 and the said holder when the pencil has been inserted in the pocket of a garment. The limbs 17 of the holder are provided with inturned ends 21, which engage in the notch 15, and this holder is secured to the reduced portion 12 of the pencil 10 by means of the sleeve 13, which is telescoped upon the said reduced portion 12 of the pencil. The ferrule or sleeve 13 at its inner end is 75 inturned at 12' to bite into the pencil so as to permanently mount the holder thereon.

The pencil is inserted in the pocket in a garment in the usual manner and the holder grips the free edge of the said pocket clamping it between the holder and the pencil, thereby sustaining the pencil fast within the pocket, but providing its ready removal therefrom.

It is clearly obvious that the holder is 90 permanently mounted upon the end of the pencil 13 so as to form a part thereof and the mounting of the said holder will not interfere with the free use of the pencil, should it be desired the holder may be 95 brought into engagement with a belt of a garment for holding the pencil upon the person when not in use without possibility of losing the same.

From the foregoing it is thought that the 100 construction and operation of the invention will be clear, and, therefore, a more extended explanation of the same has been omitted.

What is claimed is:—

The combination with a pencil having channels in opposite sides thereof opening through one end and the opposite sides of the same, of a pencil holder comprising a substantially U-shaped resilient clip having 110

its limbs seated in the said channels and provided with inturned ends abutting against the adjacent end of the pencil and a supporting ferrule telescoped upon the channeled end of the pencil and having an inturned inner end biting into the said pencil.

In testimony whereof I affix my signature in presence of two witnesses.

IDA M. HART.
